UNITED STATES PATENT OFFICE.

ALFIO GRASSO, OF OMAHA, NEBRASKA.

GASOLINE STOVE.

Application filed November 3, 1921. Serial No. 512,693.

To all whom it may concern:

Be it known that I, ALFIO GRASSO, a citizen of the United States, residing at Omaha, in the county of Douglas and State of Nebraska, have invented certain new and useful Improvements in a Gasoline Stove, of which the following is a specification.

This invention relates to an improvement in gasoline stoves, and has for its object to provide features tending to render the use of gasoline more safe than ordinary and including means convenient in use for controlling the flow to the burners of gasoline under pressure.

The invention consists of the novel construction, combination and arrangement of parts as described herein and claimed, and as illustrated in the accompanying drawing, wherein,

Fig. 1 is a plan view, partly in section, of the gasoline stove. Fig. 2 is a side view of the same. Fig. 3 is a view of the stove in transverse section. Fig. 4 is a sectional view through a valve and tank, showing one of the conduction pipes for a burner and a jacket therefor.

Referring now to the drawing for a more particular description, the invention is shown in connection with the body or frame 5 and the gas-generating pipes α of a pair of burners 6 and 7 of a gasoline stove.

I provide a chamber 8 at the back of the body or frame 5, its outer wall which is secured thereto being indicated at 9, said chamber being adapted to contain a tank 10.

Secured to the tank and extending to the respective burners 6 and 7, but not communicating therewith, are a pair of housing tubes 11 and 12, each adapted to contain an attenuated conducting pipe α communicating with the tank, near its bottom, and with a burner.

A block or valve-housing 13 is disposed outwardly of the wall 9, having a valve-seat b provided with a conduit c communicating with the tank.

Numeral 14 indicates an attenuated supply-pipe for conducting gasoline under pressure to the tank, subject to the control of a valve 15 adapted to be rotated by the rod of valve-stem 16 of the valve, the stem being provided with a thumb-piece 17.

As thus described, an operator, by rotating the valve 15 may permit gasoline under pressure to move from the single conducting-pipe 14 to the tank 10 and from thence the gasoline may move through the conducting-pipes α to the pipes α of the burners, the attenuated pipes α , on account of the housing tubes 11, being protected from injury, the supply of gasoline to each burner being uniform, and the valve 15 being arranged for convenient operation.

I claim:

The combination with the burners of a gasoline stove, of a housing having a wall secured to the upright wall of the stove, a tank within and supported by the wall of the housing, an oil supply pipe communicating with the tank, a plurality of housing tubes secured to and in non-communicating relation with the burners and communicating with the tank, a plurality of attenuated tubes each being loosely disposed in a housing tube and communicating with the tank and a burner, and means on the supply pipe to control a movement of oil to said tank.

In testimony whereof, I have affixed my signature in presence of two witnesses.

ALFIO GRASSO.
